US0D1073282S

(12) **United States Design Patent** (10) **Patent No.:** **US D1,073,282 S**
(45) **Date of Patent:** **** May 6, 2025**

(54) **INSOLE**

(71) Applicant: **Shenzhen Bixu Trading Co., Ltd.**,
Shenzhen (CN)

(72) Inventor: **Yuwei Jiang**, Dongguan (CN)

(73) Assignee: **Shenzhen Bixu Trading Co., Ltd.**,
Shenzhen (CN)

(**) Term: **15 Years**

(21) Appl. No.: **29/973,092**

(22) Filed: **Nov. 14, 2024**

(51) **LOC (15) Cl.** **02-04**

(52) **U.S. Cl.**

USPC **D2/961**
